UNITED STATES PATENT OFFICE.

WILLIAM H. DUNKERLEY, OF PATERSON, NEW JERSEY.

REELING-MACHINE.

SPECIFICATION forming part of Letters Patent No. 353,297, dated November 30 1886.

Application filed January 21, 1886. Serial No. 189,342. (No model.)

To all whom it may concern:

Be it known that I, WILLIAM H. DUNKERLEY, a citizen of the United States, residing at Paterson, Passaic county, State of New Jersey, have invented a new and useful Improvement 5 in Reeling-Machines, of which the following is a specification, reference being had to the accompanying drawings, forming a part thereof.

10 The object of my invention is to provide a reliable stopping and measuring mechanism for reeling-machines, whereby the machine will be stopped automatically when a thread breaks or when the reel has had wound thereon 15 a given number of yards of thread, according to the arrangement of the measuring devices. I attain these objects by the construction shown, which will be hereinafter explained and claimed.

20 Figure 1 of the drawings shows in elevation one end of an ordinary reeling-machine having my invention thereon, in which figure the upper and lower portions of the machine-frame, &c., are removed. Fig. 2 shows in elevation 25 part of the front of the machine with my invention attached, in which figure a portion of the machine-frame, reel, tension-rods, &c., are removed; and Fig. 3 is a part plan of the same.

25 A represents a portion of an ordinary reeling-machine having the usual frame, A', reel B, driving-shaft b, gear-wheels c c', gears d d', shaft d', traverse-bar e', crank arm e, slotted bar e', and jack-pins D'.

30 The general machine, which is constructed 35 the same as is usual with machines of the class, does not need to be further described herein.

On the traverse-bar e', I pivot a lug, g⁴, and also arrange and secure thereon by screws or otherwise slotted brackets f', in the slot of each 40 of which brackets I pivot a drop-wire, f, having a guide-eye, f², and a depending part, f³. The guide-eye f², which is formed on the upper end of the drop-wire f, is adapted to receive and guide the thread C and be supported by 45 the said thread C, while the depending part f³ of the drop-wire f is adapted to engage a cone, g', a series of which cones I arrange on a rod, g, to actuate said rod when a cone is engaged by the drop-wire f³ during the reciprocation 50 of the traverse-bar.

One end of the rod g, I pivot to the vertical arm of a bell-crank, g², while the opposite end

of the rod I arrange to slide in a bracket, f⁴, that I secure to the machine-frame. The bell-erauk g², I pivot to a depending arm, g⁶, on a pivot-stud, g⁵. The lateral arm of the bell-crank I arrange to engage and actuate a balance-lever, g³, which lever I arrange and pivot for such engagement with the bell-crank g² in the bifurcated end of a crank-arm, h. The 6c inner end of the lever g³, I link to the bell-crank g² by link r, while the crank h¹, of which the arm h is a part, I pivot on a pivot, h⁴, to a bracket, h⁵, which bracket is bolted to the machine-frame. To the crank h¹, I link by means 65 of a link, h⁶, a lever, h², having a rounded-off top part, h³, which lever I pivot to the machine-frame on a pivot-stud, h⁶. The rounded top part, h³, of the lever h² is adapted to engage and release a shifting-bar, s, having a shoulder, i, slots i' and i'', and shifting-pins d³ d⁴. The shifting-bar I arrange to slide over studs i² and i³, which studs are secured in the machine-frame. To the shifting-bar s, I secure one end of a spring, k. The opposite end of 75 the spring I secure to the frame A'.

On the driving-shaft b, I arrange and secure, by a key or otherwise, a worm, l, which meshes with and actuates a worm-wheel, l¹, which wheel has integral with it a pinion, l², which 80 pinion meshes with and actuates a gear-wheel, l³, which wheel I journal on a stud, l⁴, while the wheel l³ and pinion l², I journal on a stud, l⁵, both of which studs are secured in a standard, A², of the machine-frame. 85

The gear-wheel l³, I provide with a tooth, m, having a slot, m², to accommodate a bolt, m³, by means of which bolt I secure the tooth m to the wheel l³, and secure the said tooth adjustably to the said wheel by reason of the 90 slot m².

On a standard, A³, of the machine-frame, I journal on a stud, n², a ratchet-wheel, n, which wheel I provide with a stop-pin, n', which pin I arrange in the wheel n, to engage and actuate 95 the lever h² for stopping the machine when the reel B has had wound on the same the given number of yards of thread, according to arrangement of the measuring devices. The wheel n, I also provide with a pawl, m', to 100 keep the said wheel n from reverse motion.

The thread C having been taken from the supply-bobbin D, over and around the tension-rods o and o', through the drop-eye f² to the

reel B, in the usual way, and as shown, and the measuring mechanism having been arranged, as shown, the stopping and measuring devices are in position for automatic action.

The machine is supposed to be in motion, and the operation is as follows: As the reeling operation proceeds the tension on the thread C supports in its elevated position the end f^2 of the drop-wire f, which throws the depending part f^3 of said drop-wire f forward and away from the cones g', as shown. When a thread breaks, the end f^2 of the drop-wire f, for want of support, drops from its elevated position, when the part f^3 recedes to the rod g, and is carried by the traverse-bar e² into engagement with one of the cones g'. This carries rod g to the right, and by means of bell-crank g² actuates balance-lever g³, and places the same in position to engage lug g⁴, which lever, when thus engaged, and when moved by said lug by means of crank h⁷ and link h', draws inward the lower end of lever h², which causes the upper end, h³, of said lever to engage the shoulder i of the bar s, which action elevates the end of the shifting-bar s until the stud i² has been removed from the vertical portion of the slot i'. When this is done, the spring k, which is distended, suddenly contracts, and draws outward the shifting-bar s over the studs i² i³, and, by means of shifting-pin d⁴, shifts the belt d² from off the fixed pulley a' to its loose pulley a, thus automatically stopping the machine.

When the thread is restored, the attendant draws the shifting-bar inward, which action distends the spring k, and, by means of shifting-pin d³, shifts the belt d² from the loose pulley a to its fixed pulley a', which action starts the machine. The rod g is pushed back in position, which action, by means of bell-crank g² and link r, moves lever g³ out of engagement with lug g⁴. As the unwinding of the thread C from off the bobbins D and winding them on the reel B continues, and the reel B has had wound thereon its fixed number of yards of thread, according to the arrangement of the measuring devices therefor, the pin n' engages the lever h² and forces the lower end of the lever forward, which action on the lever causes the upper end, h³, of the lever to engage the shoulder i of the shifting-bar s and raise the end of the bar until the bar s is in position to slide over the studs i² i³, which, when done, the spring k suddenly contracts and draws the shifting-bar s outwardly, and, by means of pin d⁴, shifts the belt d² from off the fixed pulley a' to its loose pulley a, automatically stopping the machine.

That my invention may be understood, I will

state that the ratchet-wheel n is supposed to have a measuring capacity of twenty thousand yards of thread wound on the reel, or one thousand yards for each one of twenty teeth on said wheel, the two extra teeth over the twenty being necessary to set the wheel, &c. The wheel l' is supposed to have a measuring capacity of one thousand yards of thread wound on the reel at each revolution of the wheel, and, by means of the tooth m, indicates its measurement of one thousand yards of thread wound on the reel by moving the ratchet-wheel n one tooth forward at each revolution of the said wheel l', the pawl m' keeping the wheel n from reverse motions. The stop-pin n' is supposed to engage the lever h² when the cypher 0 and pawl m' meet.

If three thousand yards of thread is to be wound on the reel, the ratchet-wheel n, which is indexed, will be removed three teeth, in which case the wheel l' will be required to revolve three times, that the tooth m may take up the three teeth on the ratchet-wheel n, at which time the cipher 0 and pawl m' will meet, after which action the pin n' will engage the lever h² and stop the machine.

Having described my invention, I claim as new and desire to secure by Letters Patent—

1. The combination, with brackets f' and drop-wires f, arranged in said brackets, of the traverse-bar e², for reciprocating the brackets, lug g⁴, carried by bar e², bar e, crank-arm e, for actuating the traverse-bar, shaft d², gears d d', shaft b, rod g, and cones g' thereon, the crank g², the lever g³, link r, crank h⁷, link h', lever h², bar s, spring k, and machine-frame, as described and shown, and for the purpose set forth.

2. The combination, with lever g³ and lug g⁴, for actuating the lever, of the crank h⁷, for supporting lever g³, the bell-crank g², link r, the rod g, and cones g', and drop-wires f, brackets f', rod e², mechanism for actuating rod e², stud h⁴, link h', for actuating lever h², lever h², for actuating bar s, the bar s having rods i and slots, the studs i² i³, and the spring k, as described, and for the purpose set forth.

3. The combination, with the wheel l' and tooth m, carried by said wheel to actuate an indexed ratchet-wheel, of the ratchet-wheel n and the pin n', the stop-lever h², the shifting-bar s, the spring k, and pinion l', the wheel l', the worm l, shaft b, gears e e', reel B, studs l' l, stud h⁶, and machine-frame, substantially as described, and for the purpose set forth.

WILLIAM H. DUNKERLEY.
